UNITED STATES PATENT OFFICE.

JOSEPH C. HARBISON, OF ELDORADO, ILLINOIS, ASSIGNOR OF ONE-SIXTH TO WILLIS E. STINSON AND ONE-SIXTH TO ROBERT E. STINSON, BOTH OF ELDORADO, ILLINOIS.

PUMP.

1,215,148.

Specification of Letters Patent. Patented Feb. 6, 1917.

Application filed January 28, 1915. Serial No. 4,891.

To all whom it may concern:

Be it known that I, JOSEPH C. HARBISON, a citizen of the United States, residing at Eldorado, in the county of Saline and State of Illinois, have invented certain new and useful Improvements in Pumps; and I do hereby declare the following to be a full, clear, and exact description of the invention, such as will enable others skilled in the art to which it appertains to make and use the same.

This invention relates to pumps for supplying water from wells, and the primary object of the invention is to provide a pump operated by compressed air for forcing water, under pressure out of a well and into and out of a storage tank and a spigot or faucet for use.

Another object of this invention is to provide a construction as above specified, which embodies a float, and a rock shaft, operable by the rise and fall of said float for controlling the inlet and exhaust of compressed air into a water retaining tank, for forcing the water upwardly into the storage tank and from thence out through an ordinary spigot or faucet.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a sectional view through a well showing the improved pump applied thereto.

Fig. 2 is a cross sectional view through the operating mechanism of the pump which is positioned within the well.

Fig. 3 is a cross sectional view on the line 3-3 of Fig. 2, and

Fig. 4 is a fragmentary side elevation of a part of the operating mechanism of the pump.

Referring more particularly to the drawings, 1 designates an ordinary well which has a well platform 2 mounted upon the upper end and forming a cylinder therefor. The platform 2 supports a compressed air tank 3 which is operatively connected to an

air compressor 4, by a pipe 5 in which a valve mechanism 6 is interposed for preventing the escape of air out of the retaining tank 3 through the pipe 5.

The compressed air retaining tank 3 has communication with a cylinder 7, which is positioned in the bottom of the well and which will be hereinafter more fully described, by a pipe 8.

The cylinder 7 is suspended within the well by supporting rods 9, which are secured to and depend from the platform 2. The rods 9 are connected to transversely extending ears 10, which are formed upon the sides of the tank 7. The tank 7 has an upwardly standing projection 11 formed thereupon, which is of smaller diameter than the tank itself and has its upper open end closed by a cover or lid 12. A packing washer is inserted between the inner surface of the cover 12 and the upper surface of an annular flange 14 which is formed upon the upper edge of the enlargement 11.

A collar 15 is mounted in engagement with the under surface of the flange 14, and suitable bolts 16 extend vertically through the cover 12, the washer 13, the flange 14 and collar 15, for securely clamping them together and forming a fluid and air tight connection between the cover 12 and the projection 11.

A rock shaft 20 is supported within the extension 11 by depending brackets 21, and it has an arm 22 connected thereto upon which arm is slidably mounted a weight 23. A walking beam 24 is also connected to and carried by the rock shaft 20 and it has a link connection by means of a link 25 and a spider 26. The spider 26 is slidably carried by rods 27 and 28, which extend vertically through the tank 7 and the extension 11 and are supported thereby. The rods 27 and 28 have a second spider 29 mounted thereupon in spaced relation to the spider 26. The spiders 26 and 29 are connected by bars 30 for synchronous movement. Pins 31 are inserted transversely through and project beyond the surface of the ends of the rods 27 and 28 for limiting the downward movement of the spider 29 upon the rods.

The air pipe 8 extends into the extension 11 and has a set valve 32 mounted upon its inner end, which has a pin 33 for operating the same extending out of its lower end and positioned in the path of a finger 34 which

is carried by the rock shaft 20 for movement therewith.

An air outlet pipe 35 extends downwardly from the well platform and into the extension 11, having a valve 36 carried upon its inner end which valve is controlled by the operation of a pin 37 which projects upwardly of the valve casing. A lever 38 is pivotally supported within the extension 11 by a bracket 39, and it has one end positioned for engagement with the pin 37, and the other end positioned for engagement with the finger 34 upon the operation of the finger, as will be hereinafter more fully described. The walking beam 24 is connected by means of a rod 40 to a valve 41, which controls the passage of water through the outlet pipe 55, and is active with each operation of the rocker shaft 20 and the walking beam 24 for permitting of the passage of water into the pipe. The valve 41 is carried by the lower end of the pipe 55, for preventing the backward flow of water through the pipe 55, should the check valve 56 fail to act.

The tank 7 is provided with an opening 44 extending through the bottom thereof, which is shaped so as to form a valve seat for a disk valve 45. The disk valve 45 has a valve stem 46 connected thereto which is slidably supported by a spider 47. The spider 47 is secured to the under surface of the bottom of the tank 7. A lever 48 is pivotally connected to a depending arm 49, which is secured to the bottom of the tank 7. The lever 48 is positioned for engagement with the outstanding end 50 of the valve stem 46, for forcing the valve stem upwardly for moving the disk 45 out of the valve seat formed by the opening 44.

A rod 51 is connected to the lever 48, and extends upwardly passing through guideways 52 which are carried by the tank 7 and out of the well through the platform 2, having a handle 53 formed upon its upper end to provide for the manual operation of the rod for forcing the valve disk 45 out of engagement with the valve seat to permit of the outlet of water from the tank 7 when it is desired to move the tank from a well for repairs or other purposes.

The tank 7 has suitable supporting legs 54 secured to its base or bottom, for supporting it upwardly from the bottom of the well.

A water outlet pipe 55 communicates with the tank 7, and extends upwardly therefrom having a check valve 56 interposed therein so as to prevent the water from passing downwardly through the pipe and into the tank, so as to permit of the upward flowing of the water through the tank when forced upwardly therein by the inlet of compressed air into the tank. The pipe 55 has its elbow or T-joint 57 connected thereto, to which is connected a pipe 58. The pipe 58

is in turn connected to a storage tank 59. The storage tank 59 is positioned within the well above the tank 7 and is supported by suitable supporting rods 60, which are secured to the under surface of the platform 2 and to the tank 59 in any suitable manner. The T-joint 57 has a pipe 61 connected thereto which extends upwardly out of the top of the well and has a spigot or faucet 62 mounted thereon for controlling the outlet of water out of the pipe 61 for use.

In the operation of the improved pump heretofore described: When the tank 7 is lowered in the well, the weight of the surrounding water will lift the valve disk 45, when the air has been exhausted through the pipe 35, and the water will rise in the tank 7 until air is admitted into the extension 11 through the valve 32. The weight 23 is of such nature as to hold the float 42 against movement, when it reaches the top of the cage formed by the rods 30 and the spiders 26 and 29, after which further pressure of the water overcomes the action of the weight 23 and rises, throwing the weight 23 over, which rocks the shaft 20 and operates the finger 34 causing the latter to strike the valve stem 33 and open the valve 32. The opening of the valve 32, will, provided the tank 3 is charged with compressed air, permit the escape of the air through the pipe 8 and into the tank 7 and upon the top of the water rising in the tank, which will force the water into the outlet pipe 55 through the valve 41. The valve 41 is opened by the upward movement of the float 42, owing to the connection with the walking beam 24 through the medium of the rod 40. The water entering the pipe 55 will pass upwardly through the check valve 56 and into the storage tank 59, compressing the air which is in the tank. The check valve 56 will prevent the water from passing downwardly out of the tank 59 and into the tank 7, upon the release from the inflowing air pressure, and will hold the air compressed within the tank 59, retaining the water therein under pressure, so that upon the opening of the faucet 62, the water will rush out of the same under the pressure of the air within the tank 59. The walking beam 24, the link 25 and the spider 26 form what is known as a rule joint, which, with the action of the weight, give resistance to the float, until the start to move, when the angle of the joint becomes more acute and easier of operation. The weight also loses its force as it moves upwardly to a position directly above the rocker shaft, so that when it starts its movement, it never stops until it reaches the terminus of its movement upon the opposite side of the rocker shaft from its normal position.

As the water is used out of the storage tank 59, and the tank 7, the float 42 moves

downwardly with the dropping of the level of the water, but the rocker shaft and the valve 32 are held in operative position by the weight 23 until the float reaches the bottom of its bottom or lower terminal of its movement, when the weight of the float reverses the position of the rocker shaft 20, moving the weight 23 synchronously therewith. The rocking of the rocker shaft 20 is caused by the float 42 reaching its lower terminal, will cause the finger 34 to strike the valve stem 37, opening the valve 36 and permitting of the escape of the air therefrom. When the air is exhausted out of the tank 7, the weight of the water surrounding the tank will force the valve disk 45 upwardly and automatically refill the tank. The forcing of air into the tank, will force the weight of the water in the tank downwardly and automatically force the valve disk 45 downwardly and close the opening 44. The water flowing out of the storage tank 59 will relieve the pressure of the air therein to be again compressed upon the forcing into the tank of a new supply of water.

The combination of the various parts of the pump heretofore described, forms a pump, or water works that furnishes water under pressure at the faucet 62 as long as there is compressed air in the tank 3.

From the foregoing description taken in connection with the accompanying drawings the advantages of construction and of the method of operation of the improved pumps will be readily apparent to those skilled in the art to which this invention appertains and, while in the foregoing description, the principle of the operation of

this invention has been described together with various features of construction, it is to be understood that certain minor features of construction, combination and arrangement of parts may be altered to suit practical conditions provided such alterations are comprehended within the scope of what is claimed.

What is claimed is:—

In a pump, the combination of a tank adapted to be inserted into a well, an automatically operating valve in the bottom of said tank, a compressed air tank, said well tank connected to said compressed air tank, means for controlling the air passing from said compressed air tank into said well tank, an outlet pipe connected at its inner end to and communicating with said well tank, a valve on the inner end of said outlet pipe, a storage tank communicating with said outlet pipe, a float mounted within said well tank and means for operating said float within said well tank for operating said air retaining means for permitting of an inlet of air into said well tank for forcing the water upwardly through the outlet pipe into said storage tank and compressing the air retained therein, said float also operating the valve on the inner end of the outlet pipe permitting water to be forced in the storage tank, and a valve arranged in said outlet pipe to prevent the back flow of water from the storage tank into the well tank.

In testimony whereof I affix my signature in presence of two witnesses.

JOSEPH C. HARBISON.
